UNITED STATES PATENT OFFICE.

LAURA McQUILLAN, OF FORT SILL, OKLAHOMA.

PERMANENT HAIR-WAVING METHOD AND PREPARATION.

No Drawing.

Application filed March 14, 1924. Serial No. 699,353.

To all whom it may concern:

Be it known that I, LAURA McQUILLAN, a citizen of the United States, and a resident of Fort Sill, Comanche County, State of Oklahoma, have invented certain new and useful Improvements in Permanent Hair-Waving Methods and Preparations, of which the following is a full and clear specification.

10 The object of this invention is to provide a simple preparation and method for permanently waving human hair, as more fully hereinafter set forth.

The main preparation I use consists of 15 potassium carbonate and water, preferably in the form of about one pound of potassium carbonate to two gallons of water, thoroughly mixed. After the strand of hair is wound upon a curling-pin of the usual 20 well-known type, I saturate the wound hair with my weak preparation; then a thick coating of pure lanolin is applied directly upon the wound hair; then I cover the coated hair with a strip of cotton cloth and 25 wet flannel, absorbent cotton or other fabric; then the package thus formed is inserted in a tubular electrical heater in the usual manner to convert the water into steam, and this steam is allowed to act during a period of 30 about ten minutes.

The foregoing treatment produces a permanent curl or wave in the hair and at the same time the lanolin is steamed into the hair. I use potassium carbonate because

it works perfectly with lanolin, which, according to my experience, is the only oil which will add to the curliness of the hair. The harmlessness of my weak solution of potassium carbonate can be seen from the fact that it can be used without oil. Any 35 oil other than lanolin will uncurl hair. Lanolin being a fat extracted from wool, which is naturally curly hair, when steamed into the hair after the same has been made receptive by the softening agent and steam, 40 makes the hair more curly and as soft as naturally curly hair.

What I claim as new is:

1. The method herein described of permanently waving human hair consisting in saturating the hair while wound upon a core-pin with potassium carbonate diluted in water; then applying to the hair thus saturated a coating of lanolin; then winding a strip of wet fabric upon the lanolin coating; and then steaming the hair while thus enclosed in the fabric. 50

2. The method herein described of permanently waving hair consisting in first saturating a curled portion of the hair with a 55 lotion, then applying directly to the hair lanolin, then encasing the hair in a wet fabric, and finally steaming the whole to convert the moisture in the fabric into steam. 60

In testimony whereof I hereunto affix my signature.

LAURA McQUILLAN.
